GOOGLES

Julius E. Hansen, Rochester, N. Y.

Application July 3, 1945, Serial No. 602,957

4 Claims. (Cl. 2-14)

1

The present invention relates to goggles or spectacles and more particularly to goggles or spectacles of the type which are used as sun glasses or as protection against the wind.

One of the objects of the present invention is the provision of goggles or spectacles having eye-covering parts constructed and arranged to afford a high degree of protection of the eyes against glare and also to afford a high degree of protection of the ocular area against wind and dust. More particularly, and in accordance with the present invention, the goggles including a pair of eye-covering parts which conform to the contour of the wearer's face in the ocular area thereof, each of said parts being of such size and shape as to extend from the inner end of the eye laterally to the outer end of the eye and rearwardly from the outer end of the eye over the adjacent lateral portion of the head, rearwardly of the eye, and to extend vertically from above the eye to the portion of the face below the eye, each of said eye-covering parts being contoured so that it is positioned close to the adjacent ocular area of the face including the lateral portion of the head rearwardly of the outer end of the eye.

Another object of the invention is the provision of goggles or spectacles of the character described and which are constructed and arranged so that the eye-covering parts are foldable or relatively movable from their normal eye-covering positions to positions in which they are disposed in overlying or overlapping surface relation to form a compact article which can be disposed in a suitable protective container of a convenient size and shape to be carried in the individual's pocket or in a lady's handbag.

Another object of the invention is to provide the eye-covering parts of the goggles with compensating prisms whereby to substantially reduce light distortion, striae, etc., whereby to improve the optical quality of the goggles.

The above and other objects, features and advantages of this invention will be fully understood from the following description considered in connection with the accompanying illustrative drawings.

In the drawings:

Fig. 1 is a front perspective view of goggles embodying the present invention;

Fig. 2 is a front perspective view showing the goggles as positioned on the wearer and conforming to the contour of the face;

Fig. 3 is a view of the goggles as seen from the side of the wearer's face;

2

Fig. 4 is a plan view of the goggles in the folded condition thereof;

Fig. 5 is a top view of one of the eye-covering parts of the goggles;

Fig. 6 is an exploded perspective view of the means for connecting the eye-covering parts to each other in foldable relation;

Fig. 7 is a bottom view of the central portion of the goggles;

Fig. 8 is a view similar to Fig. 1 illustrating a modification;

Fig. 9 is a view of the goggles of Fig. 8 in the folded condition of said goggles;

Fig. 10 is a perspective view of the inner side of the central portion of the goggles, illustrating a modification;

Fig. 11 is a fragmentary end view of one of the eye-covering parts of the goggles and of part of an adjustable head band which can be provided;

Fig. 12 is a view similar to Fig. 10 showing another modification.

Referring now to the drawings in detail, the goggles 10 of the present invention comprise a pair of translucent eye-covering parts 12 connected to each other at their inner ends by the connecting device 14 and provided with temples 16 which are pivotally connected to the outer ends of the companion eye-covering parts by hinge members 18.

The eye-covering parts 12 of the goggles are preferably formed of methyl methacrylate, since this plastic has light transmission and optical qualities favorably comparable with the highest grade of optical glass and moreover is substantially lighter than glass, but it will be understood that said eye-covering parts can be formed of any other suitable plastic or of optical or other glass. Further, it will be understood that when the goggles are intended to be used as sun goggles, the plastic or glass of which the eye-covering parts are made is colored or otherwise provided with anti-glare properties. The goggles of the present invention are well adapted to afford protection against wind and dust, as well as

against glare, but it will be understood that the eye-covering parts can be formed of clear or non-colored plastic or glass when intended only for wind and/or dust protection. Also, it will be understood that eye-covering parts may be in the form of light-refraction lenses for vision-correction.

In accordance with the present invention the eye-covering parts 12 are of such size and shape as to afford a high degree of protection to the ocular areas of the wearer's face. For this pur-

pose each of said eye-covering parts is of such size and shape as to extend laterally from the inner end of the wearer's eye to the outer end of the eye and rearwardly from the outer end of the eye over the adjacent lateral portion of the head, and to extend vertically from above the eye to a portion of the face below the eye, as illustrated in Figs. 2 and 3. More specifically, each eye-covering part 12 consists of a plate having a front eye-covering part 20 which is outwardly curved laterally of said part from the inner end 22 thereof to the outer end portion 24 which is curved in continuation of the curvature of the front eye-covering part 20 with the same radius of curvature as that of said front eye-covering part of the plate and which is directed rearwardly so that the outer end 26 thereof extends to the lateral portion of the wearer's head rearwardly beyond the outer end of the eye. Thus, eye-covering parts 12 are contoured to conform to the contour of the adjacent ocular areas of the wearer's face and to lie close thereto, preferably with the outer end portions 24 of said eye-covering parts in contact with the adjacent portions of the face as illustrated in Fig. 2, to afford a high degree of protection against wind and dust as well as against sun or other glare.

Eye-covering parts 12 are preferably prismatic to compensate for light distortion, striae, etc. For this purpose each eye-covering part 12 tapers in thickness, as illustrated in Fig. 5, from the inner end 22 thereof to its outer end 26. It will be understood, however, that it is within the scope of the present invention to form the eye-covering part 12 of uniform thickness. When the eye-covering parts 12 are formed of methyl methacrylate, they are preferably formed by casting the same from liquid or monomeric methyl methacrylate which is converted into the polymeric form in the casting mold. By thus casting the eye-covering parts 12 to shape, stresses which would be present if the eye-covering parts were molded from sheet material are obviated but it will be understood that it is within the scope of the present invention to form the eye-covering parts 12 by molding the same from sheet material.

As described above the eye-covering parts 12 are connected to each other at their inner ends by the connecting means 14 and it will be noted by referring to Figs. 1 and 4 of the drawings that the eye-covering parts are pivotally connected at their inner ends to the connecting means 14 so that said eye-covering parts are foldable from their normal position illustrated in Figs. 1 and 2 to the folded condition illustrated in Fig. 4 in which the eye-covering parts are in overlying or overlapping adjacent surface to surface relation so that when the temples 16 are folded down, as illustrated in Fig. 4, a compact article is provided for insertion within a small and flat protective case or container which may be conveniently carried in the pocket of a man's jacket or shirt or in a lady's handbag. The connecting device 14, which is illustrated in detail in Figs. 6 and 7 is preferably formed of a suitable plastic and comprises an outer member 28 having a thickened portion 30, an inner member 32 and a spacing member 34. Member 28 also is provided with a thickened central portion 36 which has a curved lower edge 38 continuous with the curved lower edge of member 28 to conform to the curvature of the bridge of the nose. As illustrated in Fig. 7 the inner end portions of the eye-covering parts 12 are disposed in transversely offset relation by the thickened portion 30 and by the spacing mem-

ber 34, so that said eye-covering parts can be folded into positions illustrated in Fig. 4 in which they lie in overlapping adjacent surface relation with slight clearance between the adjacent overlapping surfaces to prevent scarring of said surfaces. Said eye-covering parts 12 are pivotally connected to the connecting member 14 by pivot pins 39 which pass through apertures in the inner end portions of the eye-covering parts and in the several companion parts of the connection means 14, member 28 having apertures 40 and 42 which register with apertures 44 and 46 respectively of member 32, and spacing member 34 having an aperture 48 which registers with apertures 40 and 44. As illustrated in Fig. 8, instead of connecting the eye-covering parts 12 pivotally to each other by the connecting means 14, said eye-covering parts may be pivotally connected directly to each other in overlapping relation at the inner ends by a pivot pin such as an eyelet 50 which passes through aligned apertures in the overlapped inner end portions 22A of the companion eye-covering parts 12.

As illustrated in Figs. 1 and 4 the eye-covering parts 12 are provided with nose-rest pieces 52 which may be formed integrally with the companion eye-covering parts or which may be initially separate therefrom and secured thereto in any suitable way. However, in order to enable the goggles to be properly worn over vision-corrective spectacles or eye glasses, the nose piece 54 may be provided as illustrated in Fig. 10 or Fig. 12, in which event the nose-rest pieces 52 may be omitted. Nose piece 54 may be formed of metal or other suitable material and secured to connecting device 14 in any suitable way as by the screws 56 which are threaded into the pivot pins 39 of the connecting means 14. Nose piece 54 instead of being secured to device 14 by the screws 56 as illustrated in Fig. 10 may be connected in quick detachable relation to device 14 as illustrated in Fig. 12 which shows the nose piece provided with a prong 57 removably fitted into a groove 58 provided in a part of the connecting device 14, preferably in the part 38 thereon, thus the nose piece may be supplied as an accessory to the goggles so that it can be attached or removed by the user thereof as desired by the latter. Also, if desired, an adjustable head band may be utilized instead of the temples 16 as illustrated in Fig. 11, which shows a looped end portion 58 of the head band B connected to the outer end portion of the eye-covering part which for this purpose is provided with a slit 60 therein. The head band B may be of any suitable type and as here shown is provided with an adjusting buckle device 62.

It will be understood that various changes in the details and construction and in the size, shape and arrangement of parts may be made in the goggles of the present invention without departing from the underlying idea or principles thereof within the scope of the appended claims.

Having thus described my invention, what I claim and desire to secure by Letters Patent is:

1. Goggles comprising transparent eye-covering individual rigid parts having front eye-covering portions and outer end and posterior portions integral with said front portions, respectively, and directed laterally and rearwardly therefrom so as to lie close to the adjacent side portions, respectively, of the wearer's head rearwardly of the eyes, in overlying relation to said side portions, each of said eye-covering portions being arcuately curved laterally thereof, said outer end

portions being curved laterally and rearwardly and extending rearwardly to positions in which they confront and lie close to the lateral portions of the wearer's head rearwardly of the eyes, the inner ends of said eye-covering individual parts being positioned to lie at the opposite sides of the bridge of the wearer's nose, a nose-piece, and separate pins pivotally connecting the inner ends of said individual parts, respectively, to said nose-piece, the pivotal axes being transverse to said parts in the direction of the inner and outer surfaces thereof, and said nose-piece being provided with portions which hold the inner ends of said parts in transversely offset relation.

2. Goggles comprising individual eye-covering parts having front eye-covering portions and outer end and posterior portions integral with said front portions, respectively, and directed laterally and rearwardly therefrom so as to lie close to the adjacent side portions, respectively, of the wearer's head rearwardly of the eyes, in overlying relation to said side portions, said eye-covering parts being each formed of substantially inflexible material and each comprising transparent front portions for visibility therethrough and integral outer end portions which are continuous with said front portions, respectively, in stationary relation thereto, each of said eye-covering parts being outwardly convex laterally thereof, said outer end portions being curved laterally and rearwardly and extending rearwardly to positions in which they confront and lie close to the lateral portions of the wearer's head rearwardly of the eyes, the inner ends of said eye-covering individual parts being positioned to lie at the opposite sides of the bridge of the wearer's nose, a nose-piece, and separate pins pivotally connecting the inner ends of said individual parts, respectively, to said nose-piece, the pivotal axes being transverse to said parts in the direction of the inner and outer surfaces thereof, and said

nose-piece being provided with portions which hold the inner ends of said parts in transversely offset relation.

3. Goggles comprising transparent eye-covering individual parts which are outwardly convex laterally of said parts, respectively, a nose-piece, and separate pins pivotally connecting the inner ends of said individual parts, respectively, to said nose-piece, the pivotal axes being transverse to said parts in the direction of the inner and outer surfaces thereof, and said nose-piece being provided with portions which hold the inner ends of said parts in transversely offset relation.

4. Goggles comprising transparent eye-covering individual parts which are outwardly convex laterally of said parts, respectively, said nose-piece having portions which are engaged by the inner ends of said eye-covering parts and which hold said inner ends in transversely offset relation, and pivot pins passing through said inner ends of said parts, respectively, transversely thereof, and through said nose-piece for pivotally connecting said parts to said nose-piece.
